UNITED STATES PATENT OFFICE

2,437,729

BELT BUCKLE

Edward M. Easter, Detroit, Mich.

Application January 10, 1945, Serial No. 572,227

2 Claims. (Cl. 24—194)

1

The present invention relates to new and useful improvements in belt buckles, and has for its primary object to provide novel means for automatically gripping and securing a belt against movement in the buckle.

More specifically, the invention comprises a hollow body through which one end of a belt is adapted for insertion together with pivotal and slidable locking means mounted in the body and adapted to produce a wedging engagement of the belt with a portion of the body to secure the belt against withdrawal.

A still further object of the invention is to provide releasable means for the belt locking means.

Another important object of the invention is to provide locking means within the body for the belt and adapted for securing the belt against movement in either direction.

An additional object is to provide a device of this character of simple and practical construction, which is neat and attractive in appearance, efficient and reliable in operation, and otherwise well adapted for the purposes for which the same is intended.

Other objects and advantages reside in the details of construction and operation, as more fully hereinafter described and claimed, reference being had to the accompanying drawing forming part hereof, wherein like numerals refer to like parts throughout, and in which:

Figure 1 is a longitudinal sectional view of the belt buckle.

Figure 2 is a top plan view.

Figure 3 is a side elevational view.

Figure 4 is an enlarged end elevational view of one form of locking member.

Figure 5 is a fragmentary sectional view illustrating a modified form of locking member showing the same in belt-locking position.

Figure 6 is a view similar to Figure 5 showing the locking member in released position.

Figure 7 is a fragmentary sectional view illustrating a modified form of releasing mechanism for the belt-locking member, and

Figure 8 is a perspective view of the form of belt-locking member illustrated in Figures 5 and 6.

Referring now to the drawing in detail, and first with respect to the form of the invention illustrated in Figures 1 to 4, inclusive, the numeral 5 designates a hollow, substantially elongated belt buckle body having openings 6 and 7 in its opposite ends to form a guide for slidably receiving one end of a belt 8 inserted through said openings and extending through the guide. The other end of the belt designated at 9 is also

2

inserted through the opening 7 and secured in the guide by means of a pin 10.

The sides of the guide are formed with inclined, longitudinally extending slots 11 having a lateral extension 12 at one end, the slots 11 being adapted to slidably and rotatably receive the trunnion 13 formed on the end of a roller 14 having circumferentially spaced, longitudinally extending ribs 15 formed thereon.

The slots 11 are inclined in a direction toward a transversely extending rib 16 formed on the inside of the guide 5 on the back wall thereof, while the lateral extensions 12 of the slots 11 extend in a direction toward the front wall of the guide.

Accordingly, by inserting the end 8 of the belt through the opening 6 and into the guide 5, the belt will pass over the rib 16 and under the roller 14 whereby upon sliding the roller along the slots 11 and into the lateral extensions 12, one of the ribs 15 of the roller will wedge the belt against the rib 16 and thus secure the belt against movement in the buckle.

The rib 16 may be formed with serrations or teeth 17 and the ribs 15 of the roller 14 may likewise be formed with serrations or teeth 18 to more effectively bite into the surfaces of the belt.

Inclined flanges 19 may be formed on the inside of the guide 5 and extending upwardly from the rear wall thereof to guide the end 8 of the belt into a position for feeding the same through the rear opening 7.

In the form of the invention illustrated in Figures 5 and 6 of the drawing, the locking member is designated at 20 and is in the form of a pair of diverging plates 21 having trunnions 22 at their longitudinally connected edges for sliding and rotatable movement in the inclined slots 23 in the opposite side of the hollow guide 24.

The plates 21 constitute legs adapted to straddle the inwardly struck rib 25 formed on the rear wall of the guide 24 when the trunnions 22 are moved into the lateral extensions 26 of the slots.

When in the position shown in Figure 5 of the drawing, the legs of the locking member 20 will prevent sliding movement of the belt 27 in either direction.

An inwardly projecting stop pin 28 carried by the guide 24 and positioned between the legs 21 limits the swinging movement of the legs in either direction.

The trunnions 22 of the locking member are released from the lateral extensions 26 of the slots 55 by means of a lever 29 pivoted to the inside of the

guide 24 and projecting outwardly through the front wall thereof by way of an opening 30 therein, the lever having a laterally projecting lug 31 thereon engaging the connecting edges of the legs 21 to force the same out of the lateral extensions 26 so that the trunnions 22 may move along the slots 23 to disengage the legs from the belt.

In the form of the invention illustrated in Figure 7, the releasing means for the locking member comprises a button 32 working in an opening 33 in the front wall of the guide 34, the button having one end of a leaf spring 35 embedded therein and which is secured at its other end to the inside of the guide. An inward movement of the button 32 will engage the locking member (not shown) which has its ends adapted for movement in the slots 36 to disengage the locking member from the lateral extensions 37 of said slots.

It is believed the details of construction, manner of operation and advantages of the device will be readily understood from the foregoing without further detailed explanation.

Having thus described the invention, what is claimed as new is:

1. A belt buckle including a belt guide adapted for slidably receiving one end of a belt, a transverse rib in the guide, and a locking member including diverging legs and having trunnions slidably and rotatably mounted in the guide for movement of the locking member toward and away from said rib, said legs straddling the rib and adapted for wedging a belt against the rib upon exertion of a pulling force on the belt in either direction, and means on the guide operable outwardly of the latter for engaging and releasing said locking member.

2. A belt buckle including a belt guide adapted for slidably receiving one end of a belt, a transverse rib in the guide, and a locking member including diverging legs and having trunnions 5 slidably and rotatably mounted in the guide for movement of the locking member toward and away from said rib, said legs straddling the rib and adapted for wedging a belt against the rib upon exertion of a pulling force on the belt in either direction, and a pivoted lever carried by the guide and having a portion engaging the locking member for releasing the same.

EDWARD M. EASTER.
